STEAM GENERATOR

Charles E. Lucke, New York, N. Y., assignor to
 The Babcock & Wilcox Company, Bayonne,
 N. J., a corporation of New Jersey

Application February 27, 1931, Serial No. 518,623
 Renewed July 1, 1936

4 Claims. (Cl. 122—235)

This invention is a drumless steam generator of the once through type having several successive heat transfer sections through which the fluid, as it is being converted into vapor, at high pressure and temperature, progresses in sequence from entrance to outlet with no recirculation, the vapor emerging as superheated steam.

With boilers of the aforesaid type, difficulty has been experienced in delivering steam of proper superheat, due to the fact that the location at which steam generation ceases and superheating begins may vary; and then too, the different sections of the steam generator may have divergent heat transfer characteristics with the result that the mixture of steam from the several sections may have an indefinite, different, or changing quality, seriously interfering with the proper utilization of the same in turbines and the like, unless a corrective or equalizing superheat is imparted to the mixture at a predetermined location safe from overheating, which feature constitutes an object of the present invention. The zones where evaporation has been completed must be protected against overheating even if they vary in position during operation.

Also, the arrangement of the several sections constituting the once through flow of entering cold water and emerging superheated steam, in connection with the travel of the gases of combustion from which the heat is taken, represents another phase which forms an object of this invention.

And, furthermore, the provision of a furnace having a continuously progressive gas passage from heat source to gas exit arranged in loops, with heat transfer sections disposed in and about the gas passage, and cold water entering the generator in that section disposed in the cooler end of the gas passage and traversing successively convection, radiant and convection heat transfer surfaces until converted into superheated steam, constitutes another object of the invention.

Maximum use of heat transfer tubes to comprise furnace walls and thus minimize the difficulties and expense of refractory structure is another object, as is also cutting down of heat storage in the refractory walls whereby the steam generator is rendered quickly responsive to changes in load.

Such a boiler as constitutes the subject of this invention is well suited for the highest steam pressures and temperatures required for the most efficient power plants, and it is especially well adapted to the very large capacities required by

central station practice where the tendency is to concentrate all steam generation, for a single large turbine, in one boiler.

With the foregoing, and other objects in view I shall now describe one embodiment of the invention which I have illustrated somewhat diagrammatically in the accompanying drawings for the purpose of disclosing the invention, and wherein—

Fig. 1 is a transverse section in a vertical plane 10 from front to rear of the boiler; and

Fig. 2 is a sectional view on the line A—A of Fig. 1.

The generator illustrated in the drawings as embodying the invention comprises a furnace 15 formed of the enclosing bottom 1, top 2 and side walls 3, 4, 5 and 6, with an upright partition 7 which ends below the top 2 leaving a horizontal gas passage 8 connecting the two vertical gas passages 9 and 10 for upflow and downflow of 20 gases, respectively delivered from the combustion area in which are located fuel burners 11. The back wall 6 stops short of the bottom 1 whereby there is provided a horizontal gas passage 12 leading to the flue 13 in which there may be 25 disposed an air heater 14, the gases of combustion passing upwardly therethrough and out at 15 while the air enters at 16 and is turned by the baffles 17 to pass downwardly countercurrent to the gases of combustion past the guiding vanes 18 and out at 19 heated to the proper degree for 30 use in promoting combustion.

The generator tubes are arranged in sections in the order hereinafter described, the water entering the economizer section 20 as indicated at 35 21 being fed by means of the usual feed pump, not shown.

The economizer section 20 is located in the cooler end of the downwardly extending gas passage 10 and is comprised of a group of parallel 40 vertically arranged series coils of the serpentine or return bend type, each indicated at 22 and originating in the header 23 connected with the water feed inlet 21 and terminating in the upper header 24 connected with a pipe 25 leading to the upper header 26 of the slag and superheater screen 27.

The slag screen 27, which also screens the superheater so that it is protected against overheating by radiant heat, as shown, is disposed in the upwardly extending gas passage 9, and the water connection from the economizer 20 is connected as stated by the pipe 25 to the upper header 26 thereof so that the circulation of water, as will be hereinafter noted, is countercurrent to 50 55

the gas flow in both the economizer and the slag screen. The slag screen 27, like the economizer 20, also comprises a plurality of parallel vertical arranged series coils of the serpentine or return bend type issuing from the upper header 26 and entering the lower header 28 from which the pipe 29 leads the water or mixture of steam and water to the radiantly heated section 30.

The section 30 in the radiant heat zone is a group of parallel tubes extending between entering header 31 connected with the pipe 29 and the outlet header 32, the tubes 30 being located in close proximity to the under surface of the top or roof wall 2 and covering the area at the turning point of the gases or the horizontally extending passage 8 connecting the upwardly and downwardly extending gas passages 9 and 10, respectively, and the steam and water from this primary or radiantly heated section 30 passes from the header 32 to the vertical header 33 of the back wall section 34, the headers 32 and 33 being connected together as at 35.

The back wall tube section 34 comprises the receiving header 33 and the exit header 33' connected together by a group of parallel tubes forming the section 34 and lying close to the wall as is the case with the tubes 30. The water or steam and water mixture issues from the exit header 33' through the pipe 35' which is branched as at 37, 38, 39 and 40 to feed the radiantly heated side wall sections disposed in the manner to be presently described.

The radiantly heated side wall sections are four in number and comprise groups of parallel tubes, vertically extending, and lying closely proximate their respective walls of the furnace. The wall tube section 41 lies adjacent the front wall 3 and includes the lower header 42 and the upper header 43 connected by the said tubes 41, the lower header 42 receiving water or steam and water from the preceding sections through the branch 37 from the pipe 35' by means of the short branch 40, the steam and water traveling upwardly through the tubes 41 to the header 43, and the water decreasing progressively; the wall tube section 44 lies adjacent the back wall 7 and includes the lower header 45 and the upper header 46 connected by the wall tubes 44, and this wall section is distinguished from the other in that, at its upper portion it crosses the horizontal gas passage 8 and therefore some provision must be incorporated for affording adequate transmission of the gases of combustion through the tube screen formed thereby, consequently, the upper portions of these tubes 44, where they cross the horizontal gas passage 8, are alternately bent or offset as shown at 47 and 48 to facilitate the passage of gases of combustion therebetween without too much resistance. The wall tube section 44 receives its supply of water or steam and water from the pipe 35' through the branch 38 leading to the lower header 45 so that, like wall tube section 41, the passage of steam and water is upwardly through the wall tube section, and the water decreases progressively as steam generation occurs. The remaining wall tube sections are side wall tube sections 49, the tubes of which are bent aside to permit the entrance of burners 11, as shown, and which tubes connect lower header 50 and upper header 51, water or steam and water entering the lower header 50 through the connection 39, and the remaining side wall tube section being indicated at 52, the tubes of which connect lower and upper headers 53 and 54 respectively, with steam and water

entering the lower header 53 through the connection 54.

It will be apparent, from the foregoing description, that all the side wall sections are comprised of parallel tubes divided into groups and with water or steam and water flowing in at the bottom headers and steam out at the top headers, which latter is assured by the proportions of the several sections of the heating surface one to another, and to the size of furnace or heat developed therein.

A convection superheater 55 is disposed in the entrance to the downflow gas passage 10 in advance of the economizer 20 and comprises a lower header 56 and an upper header 57 connected by parallel vertically arranged serpentine or return bend type tubes. This is wholly screened from radiant heat from the furnace by the screen 27 and by the roof and side wall tubes of the upper chamber over and in advance of the superheater.

Steam leaving the radiantly heated side wall tube sections 41, 44, 49 and 52 through their respective upper headers is accumulated and joined by the connections 58, 59, 60, 61, 62 and 63 so that it enters the pipe 64 leading to the lower header 56 where the steam, which is mixed in transit through the pipe 64 and in the header 56 may have, through such mixing, some superheat even though the degree of superheat of the steam from the several sections might be different until joined, and in this convection superheater there is imparted to the accumulated steam a final temperature or superheat whereby the steam leaving the convection superheater 55 through the steam outlet 65 has a definite superheat value as required by the turbine.

While in the foregoing I have described a specific arrangement of steam generator of the drumless type, it is nevertheless to be understood that the positions of the boiler components comprising the generating surface may be altered with respect to each other, or with respect to the gas passage, without departing from the spirit of the invention as defined in the appended claims.

I claim:

1. In combination, a forced flow vapor generator including a furnace receiving and radiantly burning elements of combustion, a gas passage having a 180° gas turning zone connecting the same with said furnace, a fluid passage comprising groups of tubes with the tubes of each group in parallel and one of said groups having parallel lengths disposed along the walls of the furnace, said groups successively connected for serial progression of the fluid therethrough from liquid entrance to vapor outlet, one of said groups being located transversely of the furnace wall tubes in advance of the gas turning zone and across the path of the gases to form a radiant heat shield for another of said groups across the gas passage beyond the gas turning zone, the said last two mentioned groups being spaced marginal to the turning zone to provide therein an unoccupied chamber whereby the gases passing through the first of the last two mentioned groups are enabled to become evenly distributed throughout the area of the succeeding group crossing the gas passage.

2. In combination, a forced flow vapor generator including a furnace receiving and radiantly burning elements of combustion, a gas passage having a 180° gas turning zone connecting the same with said furnace, a fluid passage comprising groups of tubes with the tubes of each group

- in parallel and one of said groups having parallel lengths disposed along the walls of the furnace, said groups successively connected for serial progression of the fluid therethrough from liquid entrance to vapor outlet, one of said groups being located transversely of the furnace wall tubes in advance of the gas turning zone and across the path of the gases to form a radiant heat shield for another of said groups across the gas passage beyond the gas turning zone, the said last two mentioned groups being spaced marginal to the turning zone to provide therein an unoccupied chamber whereby the gases passing through the first of the last two mentioned groups are enabled to become evenly distributed throughout the area of the succeeding group crossing the gas passage, some of the aforesaid groups providing a cooling tube surface for the sides of the said unoccupied chamber.
3. A forced flow vapor generator comprising walls forming a furnace and adjacent gas flues in parallel relation, means radiantly firing the furnace, a continuous fluid flow conduit receiving liquid at the cooler end and delivering superheated vapor at the other end, said conduit including sinuous portions horizontally arranged across the flues and connected for fluid flow always countercurrent to gas flow while the fluid moves progressively from a cooler portion in one flue to a hotter portion nearer the furnace outlet and some of which are heated by convection, tubes longitudinally of the walls in the radiant heat area, and a superheater intermediate the convection portions and arranged for fluid flow
- transverse to the gases passing the same while connected for fluid flow countercurrent to the gases, the said longitudinally disposed tubes and the superheater being a part of the aforesaid continuous fluid flow conduit.
4. In combination, a forced flow vapor generator including a furnace receiving and radiantly burning elements of combustion, a gas passage having a 180° gas turning zone connecting the same with said furnace, a fluid passage comprising groups of tubes with the tubes of each group in parallel and one of said groups having parallel lengths disposed along the walls of the furnace, said groups successively connected for serial progression of the fluid therethrough from liquid entrance to vapor outlet, one of said groups being located transversely of the furnace wall tubes in advance of the gas turning zone and across the path of the gases to form a radiant heat shield for another of said groups across the gas passage beyond the gas turning zone, the said last two mentioned groups being spaced marginal to the turning zone to provide therein an unoccupied chamber whereby the gases passing through the first of the last two mentioned groups are enabled to become evenly distributed throughout the area of the succeeding group crossing the gas passage, another of said groups being located beyond the last mentioned groups and connected for fluid flow countercurrent to the direction of passage of the gases thereover and thence connected to the first of the aforesaid groups.

CHARLES E. LUCKE.
